FASTENING INSERTING MACHINE

Elmer R. Pope, Hamilton, Mass., assignor to
 United Shoe Machinery Corporation, Paterson,
 N. J., a Corporation of New Jersey

Application June 14, 1929. Serial No. 370,829

52 Claims. (Cl. 12—19.2)

This invention relates to machines for inserting such fastenings as nails, and is particularly concerned with apparatus of the character of that disclosed in a patent issued in my name on November 24, 1925, and numbered 1,562,516. This apparatus is especially adapted for nailing the heel-seats of shoes.

In the machine described in the above-identified patent, the seat-securing nails are separately inserted by mechanisms movable along right lines, these mechanisms being independently located, to determine the points at which the nails are to be driven in shoes of different sizes, by contact with the shoe operated upon. In such organizations there are two very important considerations. The nailing mechanisms must occupy relatively little space laterally, to permit the nails to be inserted close to each other, so a considerable number may be employed, and, as the size of the work varies, the distance of the nails from the rand-crease and of the forward nails from the breast-line should be approximately constant. The first of these conditions lends itself to a tight crease, while the second gives most secure attachment of the sole at the corners of the heel-breast, which are subjected to the greatest displacing strains. An object of my invention is to provide for the close placing of nails or other fastenings along a series by inserting sections or mechanisms, and for the maintenance of their distance from the crease and from the breast-line approximately constant, with a uniform spacing between the fastenings of the series. To accomplish this, I arrange each fastening-inserting mechanism to move relatively to the support carrying the work, about an axis individual to such mechanism, the axes about which the various mechanisms move being substantially parallel. The work-support or jack is preferably movable, traveling vertically toward and from a generally horizontal abutment or die-block, with which it co-operates, and the axes of oscillation of the mechanisms extend in the direction of movement of the support. With this arrangement, closely placed mechanisms may, without interference, be swung in and out along curved lines, these paths keeping the points of fastening-insertion in the heel-portions of shoes similarly spaced from both the rand-crease and the breast-line for all sizes.

It is a further object of the invention to space the fastenings accurately in the seat or other shoe-portion, regardless of lack of symmetry of adjacent gaging surfaces. I accomplish this by positioning one of plural fastening-inserting

mechanisms by contact with the work and causing engagement between the thus-located mechanism and an adjacent mechanism to position the latter. This locating effect of one mechanism upon another may be continued throughout a series. With such an organization, by establishing the gaging contact with such work as a shoe at the rear of the counter-portion, where departures from symmetry are negligible, the location of the other nailing mechanisms may be invariably at the points desired. The positioning is obtained by a work-contact member, as a roll carried by one mechanism, and cooperating contact means, preferably including cams associated with the other mechanisms. Whatever contact members or means may be employed, means is preferably provided for fixing one and, if desired, all of these in different positions. In this way, the relation of the series of mechanisms as a whole to the work, and of the mechanisms in the series to one another, may be altered. Thus, the best relation of the points of nail-insertion may be attained. One of the adjustments of the mechanisms with respect to the work may be by varying independently their axes of oscillation. For this purpose, the mechanisms of the present embodiment of the invention are mounted upon eccentrics, arranged to be fixed in different rotary positions. To produce the movement of all the mechanisms toward the work, means, as a spring, may act upon one of the series and force the associated mechanisms toward one another, and finally the work-contact member against said work. Similarly, a single connection, as to the work-contact member, may be utilized to separate the mechanisms normally from the support, and thus allow the work to be brought to operating position thereon without danger of its being marred by rubbing contact with the mechanisms. As illustrated, this connection is acted upon by the movable work-support, it being made to a vertically movable jack-carrying cross-head. To prevent the movement of the support just referred to from defacing the work by forcing it against the gaging contact member carried by one mechanism of the series, and to keep this contact close to the crease, where the vertical curvature is substantially symmetrical at opposite sides of the upper, this member may be movable vertically upon its spindle or other mounting. This allows the member to travel with the support at such times as when clamping pressure is being applied to the work in preparation for driving the fastenings.

Another object of my invention is to prevent

110

displacement of the fastening-inserting mechanisms during the driving operation, and this I effect by associating with the mechanisms a positive locking member acting in the movement of the member which actuates the inserting mechanisms. Herein is disclosed such a member in the form of a wedge movable between one of the inserting mechanisms and a relatively fixed member, preferably a portion of the die-block, said member and inserting mechanism having contacting surfaces intersecting the direction of movement of the mechanism.

In nailing the heel-portions of shoes, as the heel-seats, a comparatively small change in the angle of the work about a vertical axis from the proper position will seriously affect the symmetrical relation of the nails to the crease of the shoe. As a further object of the invention, there is furnished means whereby the operator may readily and accurately locate a shoe for the operation upon it, and without the necessity for giving it special consideration. For this purpose, I associate with the shoe-support and nailing mechanisms a gage member having a portion arranged to contact with opposite sides of a shoe on the support, the opposite contact-surfaces of the gage diverging outwardly in the direction of the support. This member may be so located that it engages a shoe adjacent to the breast-line, near points where the opposite sides of both right and left shoes are equidistant from the longitudinal axis of the shoe-bottom. When the support presents a shoe for nailing, if this is displaced angularly or laterally, it will, upon entering the throat between the contact-surfaces, be caused by the action of the surfaces to be moved until it is correctly disposed with respect to the nailing mechanism. To avoid interference of the gage with the movement of the support, it is preferably yieldable in the direction of such movement.

As still another object of the invention, I provide for the maintenance of a symmetrical disposition of the nailing at opposite sides of the heel-portion of a shoe when this shifts laterally under pressure preparatory to the insertion of the nails. This movement may be caused, for example, by irregularities in the cone of the last. To prevent this lateral displacement, the shoe-supporting jack has a top connected to it by a universal joint. The contact-surfaces of the joint are curved about a point lying, during the nailing operation, substantially in the pressure-surface of the abutment or die-block, against which the jack forces the work. Consequently, as the jack-top swings to accommodate itself to the work, said top may rock so opposite sides will rise and fall, but the axis of the heel-portion remains coincident with this axis at the die-block, and there is no displacement of the points of insertion of the nails in the heel-portion.

A single embodiment of my invention appears in the accompanying drawings. Here,

Fig. 1 shows in partial front elevation the more essential portions of a nailing machine to which the present invention is applied, certain elements being in section;

Fig. 2 is a front elevation of the die-block and more closely associated parts;

Fig. 3 is a transverse section on the line III—III of Fig. 2, the pressure-head being lowered, and a portion of a lasted shoe shown in operating position;

Fig. 4 is a sectional detail at one of the locking wedges;

Fig. 5 is an irregular horizontal section taken above the die-block;

Fig. 6 illustrates somewhat diagrammatically the relation of one of the series of inserting sections to the work;

Fig. 7 is a broken perspective view showing the manner of positioning and adjusting the nailing sections; and

Fig. 8 is a broken front elevation of the machine.

The general characteristics of the machine which I have chosen to disclose herein may be substantially those of the apparatus of Patent No. 446,885, Pope, February 24, 1891. This includes a frame 10 having separated portions, between which extends a horizontal die-block 12 furnishing an abutment, against the under side of which is pressed the heel-seat of a shoe S to be nailed. At the area of contact of the heel-seat with the die-block is shown a recess 14 formed at the under side of the block, this recess serving as a mold which, as a result of the pressure applied during the nailing operation, imparts to the heel-seat the contour of the concave end of the heel which is to be later attached. The shoe S is carried upon a jack-post 16 mounted to move in ways 17 extending from front to rear of the frame, the ways being at the top of a cross-head 18 arranged to reciprocate vertically in the frame. With the cross-head in its lowered position and the jack drawn out, the shoe to be operated upon may be placed upon said jack and then pushed along the ways 17 until the heel-portion is beneath the recess 14. In this position, the machine may be operated to apply pressure to the heel-seat to form it and hold it for the insertion of the nails. When there is no last-pin on the post 16, as is herein disclosed, said post may be clamped in place on the cross-head beneath the die-block, and the shoe introduced above it into operating position.

The die-block is preferably formed in horizontal sections, joined by bolts 22. At the rear of the block are shown three passages 24 contained in bushings 26 extending through the die-block (Fig. 3). These passages are situated above the rear of the heel-seat and are inclined downwardly and inwardly. At the upper extremity of each passage 24 is a downwardly converging throat to receive a driver 28 fixed on the lower portion of a head 30 secured at the center of a top girt or yoke 27 carried by vertical side rods 29, 29 movable in the frame at the ends of the die-block. This top girt and head are reciprocated by the side rods under the power of the machine after the cross-head 18 has been raised to place the work under pressure. Above the recess 14, and extending at each side thereof between the block-sections, is a space in which are mounted for independent horizontal movement nail-inserting mechanisms, each possessing a body-section 32 and a supporting portion or arm 34 projecting outwardly and rearwardly therefrom at a somewhat obtuse angle. The arms are arranged to oscillate about vertical spindles 36 extending between the upper and lower block-sections. An adjustment may be provided for each of these axes of oscillation, the purpose of which will later appear. A portion 38 of the spindle, about which each arm 34 turns, is eccentric with respect to the spindle-ends which are in the die-block, and the angle of the eccentric may be varied by turning the spindle and fixing it in position by a clamping nut 40 threaded upon its upper extremity.

In each body-portion 32 is a nail-receiving passage 42 terminating at its lower end in a nozzle 44, in which the nails N are held in preparation for driving. These nozzles move with the 5 sections in proximity to elongated openings 45 in the under side of the die-block, the openings extending in two series along the opposite sides of the recess 14. Each passage 42 is preferably inclined downwardly and inwardly, so that the fastenings 10 in the nozzles will be driven toward the interior of the shoe, and not along or in the direction of the counter-portion. By this arrangement, the heel-seat-securing fastenings may be inserted close to the edge of the outsole, to produce a tight rand-crease, without danger of their 15 emerging through the upper. The same effect is produced by the inclination of the fixed passages 24. Nails are delivered directly to the rear passages, and to the passages 42 through communicating passages 46 extending up from the driving passages, by loader mechanism 48 arranged to turn about one of the side rods 29. Mounted to move in each passage 42 is a driver 20 secured in the lower extremity of a plunger 52 reciprocable in the corresponding section and held normally above the lower extremity of the nail-delivering passage 46 by a spring 54 surrounding it. To drive the nails through the nozzles into the heel-seat of a jacked shoe, the drivers 30 are simultaneously depressed by contact of the under side of the head 30 with the upper ends of the plungers 52. The drivers 28 at the same time insert the nails in the passages 24.

It is desired that all the two side series of nails 35 inserted by the sections 32 shall be placed in the outsole close to the rand-crease and substantially uniformly spaced therefrom for all sizes of shoes. For the rear nails inserted by the drivers 28 the location changes little with different sizes, 40 the work being gaged from this extremity by contact with a back-stop 55 adjustably mounted upon the rear of the frame at the back of the die-block. The relation of the sections of each of the side series as a whole I determine by engagement 45 of one of the sections with the counter-portion of the shoe operated upon, and the companion sections of the series by engagement with the thus-located section and with one another. I have chosen the rear section of each series for 50 engagement with the work, since this part of the counter-portion of a shoe-upper is invariably substantially symmetrical at its opposite sides. As the upper curves forward from the rear, one side of the counter-portion may project more 55 over the crease than the other, so that, if the gaging be by direct contact with the work throughout the series of nailing sections, the symmetry of the points of insertion with respect to the crease would be destroyed. Depending 60 from the under side of each rear nailing section 32 is a projection 56 (Fig. 7), extending below the die-block. Adjustable laterally of the projection, by virtue of a slot 58 and a clamping screw 60 threaded into the end of the projection, is a 65 block 62 carrying at the upper side of its inner end a contact-roll 64. The periphery of the roll is preferably inclined downwardly toward its axis to more closely conform to the inclination of the surface of the shoe-upper which it is to engage. The roll turns about a spindle 66 rising 70 from the block 62, and, since the jacked work rises for the application of pressure after the roll and shoe-upper are in contact, said roll is allowed to move longitudinally of its spindle. There is, consequently, no rubbing of the work- 75

surface over the roll, doing away with the liability of marring the former. Moreover, the roll is caused to remain close to the crease, where the outward curvature of the upper is approximately the same at both sides. This avoids displacing the work laterally, because of considerable variations in form which may occur farther from the crease. At the forward side of the block 62 is a rounded contact-projection or boss 68, which is engaged by an inclined cam-surface 70 upon a plate 72 secured to a downward projection 56 from the next section and in a manner similar to that of the rear section, except it may be made non-adjustable. At the opposite end of the plate 72 from the cam-surface 70 is a cam-surface 74, which, in turn, engages a rounded projection 76 formed upon the adjacent extremity of a plate 78 secured upon the succeeding section. A cam-surface 80 upon the outer side of the plate 78 acts upon a roll 82 surrounding a depending projection of the last or forward section of the series. All the projections are respectively individual in their sections and their cam-surfaces are shown as inclined outwardly and rearwardly from the breast-line of a shoe on the jack-post. Engagement of the roll 64 of either series of nailing sections with the counter-portion of a jacked shoe and of the various contact means of this and the succeeding sections with one another is yieldably effected by a spring 84 (Fig. 5) situated in a bore in the forward portion of one side of the die-block, this spring being seated at one end against a screw 86, and at the other extremity forcing a plunger 88 against the depending portion of the corresponding forward nailing section. 100 To produce normal separation of the sections to give a space into which the jacked shoe may be moved, without engagement with any part of said sections, the rear section of each series is joined by some such connection as a flexible member 90 to the cross-head 18 carrying the jack-post. When the cross-head is depressed, before the machine is put in operation, the pull upon the members 90 draws out the rear section of each series, and this movement is communicated by the co-operating contact means through both series of sections, carrying them all to their inactive positions against the expansive force of the springs 84. After the work has been placed upon the 105 jack-post between the sections 32 and the machine started in operation, the elevation of the cross-head with the post and work relaxes the pull upon the members 90, allowing the springs 84 to force all the sections in until the rolls 64 engage the counter-portion of the shoe, and the 110 companion sections are correspondingly located by their cam-surfaces and co-operating projections. Included in each of the flexible members 90 is a spring 92, the elongation of which compensates for any difference in the amount of 115 travel between the cross-head and the rear sections.

The axes of the spindles 36, about which the nailing sections oscillate, may be determined by fixing the desired point of insertion of each nail 120 for the extreme sizes of shoes to be operated upon, as these shoes would be located for nailing, and employing for each axis the center of an arc x passing through each pair of points (Fig. 6). The radius y of each arc takes into 125 consideration the dimensions of the die-block and associated elements, and the path through which each section should travel to avoid interference with the closely spaced adjacent sections. When thus arranged, as may be seen from 130

135

140

145

150

- a consideration of Fig. 6 of the drawings, the respective points of insertion *a* and *b* of the nails may be spaced for the proper proportionate distance from both the rand-crease-lines *c* and from the breast-lines *d* of the largest shoe *S* and the smallest shoe *s* and for the intermediate sizes. By oscillating the sections about individual vertical axes parallel to the direction of movement of the work into and out of nailing position, closely placed sections may be located side by side without interference with one another, so a suitable number of nails to obtain secure attachment may be employed. The cams upon the section-plates 72 and 73 are so designed that, the correct location of the rear section 32 having been attained by the engagement of its roll 64 with the shoe-upper, the remaining sections of each series will be positioned by contact with this section and with one another, they thus being rendered independent of the form of the counter-portion at opposite sides, both as to vertical and horizontal contour. Adjustment of the rolls 64 by the connections at 58 governs their normal relation to the cam-surface 70, and therefore the location of the entire series with respect to the spacing of the nailing points toward and from the crease and breast-line, the forward sections being controlled in this respect from the rear section. A further individual adjustment as to this spacing is obtainable by a variation in the axes of oscillation of the sections through the eccentrics 38. It should be noted that for any particular nailing design, such adjustments are unnecessary, and that the contact means, furnished by the roll 64 and the succeeding surfaces 68, 70, 74, 76, 80 and 82 which control the positions of the sections, might all be formed as integral portions of said sections.
- As the jack-post 16 is carried in along the ways 17 with a shoe upon it, the longitudinal axis of the bottom of said shoe should substantially coincide with the corresponding axis between the opposite groups of nailing sections. An angular displacement of the work will cause the points of insertion of the nails to approach one side of the heel-seat and retreat from the opposite side and affect the desired relation to the rand-crease. To enable the operator to gage the work without effort, there is mounted near the front of the die-block 12 a member 96 having a stem 98 movable along a vertical bore, but held against turning therein. A spring 100 interposed between the spindle and the upper extremity of the bore holds the member normally in its lowest position, at which it is adapted for engagement with the smallest size of shoe to be nailed, as well as the largest. The member 96 is in the form of an inverted yoke, having at its ends, in symmetrical relation to the opposite series of nailing sections, upwardly and inwardly converging surfaces 102, 102. These surfaces are so placed that the heel-end of a jacked shoe enters between and contacts with them at points adjacent to the breast-line and approximately equidistant from the longitudinal axis of the shoe. These points may readily be found and are the same for both right and left shoes. The length and inclination of the gaging surfaces 102 are such that these receive contact of all widths of shoes. Therefore, when the work is advanced between them against the back-stop and lifted toward the recess 14 by the elevation of the cross-head, the shoe is, if displaced laterally or angularly, shifted upon the post until its

longitudinal axis is correctly alined. As the upward movement continues, the member 96 yields against the spring 100, so that the proper molding contact with the recess 14 is insured for all shoe-sizes.

The shoe upon the jack-post 16 having been elevated by the cross-head 18 so the heel-seat is forced into the die-block-recess, the nailing sections are relieved from the pull of the members 90 and allowed to move into nailing position under the influence of the springs 84. Outward displacement of the sections through the forces applied in driving the nails must be prevented. This I accomplish positively by the following means: Arranged to slide vertically at each side, near the forward edge of the head 30, is a wedge member 104. Each wedge is yieldable against a spring 106 situated in a recess in the member and abutting at its upper end against the top of the bore in which the member moves. As the head descends, the tapered extremity of each of the wedges passes between the outer side of the corresponding forward section 32 and some such relatively fixed surface as the vertical wall of the recess in the die-block in which the sections move. The angle of inclination is such that the force exerted by the sections against the wedge cannot displace it, so the entire series is effectively locked for the insertion of the nails by the drivers. Different positions of the forward sections for different sizes of shoes operated upon are provided for without impairing the positive locking effect by the yield of the springs 106, allowing the wedges to remain at rest while downward travel of the head continues.

When pressure is applied to the work through the rise of the jack-post 16, it is desirable that the surface of the post which contacts with the cone of a last *L*, upon which a shoe is presented to the machine, shall be able to accommodate itself to varying inclinations of contact-surface of the cone. For this purpose, the post has, mounted upon its upper extremity, a top 108 provided with an upper contact-surface 110. The top is universally movable upon the post by a joint 112 having a socket 112 in the post to receive a partly spherical portion 114 on the under side of the top. A tension-spring 116, uniting the post and top, allows the latter to tilt in all directions from its normal position, in which the surface 110 is horizontal, and thus furnish perfect engagement with the contact-surfaces of all last-cones. Unless the universal connection were properly organized, lateral movement of the work, caused by the shifting of the top, might throw the points of insertion of the nails to one side or the other and thus interfere with the desired relation to the rand-crease. To prevent such an effect, I curve the contacting surfaces of the socket 112 and ball 114 upon arcs, the common center of which is substantially in the contact-surface of the recess 14 and at the longitudinal axis separating the series of nailing sections. Consequently, while the points of insertion may rise and fall somewhat, as the jack-top moves, their lateral relation remains practically unchanged, and the symmetry of the nailing is unaffected.

In using the machine illustrated as embodying this invention for nailing the heel-seats of shoes, a lasted upper *S* is placed with the last-cone upon the top 108 of the jack and located with respect to the nail-inserting means by the back-stop 55. At this time, the movable nailing sections 32 are held in their outward positions, re-

- moved from the jack, by the tensioned connections 90 to the cross-head 18. These connections act directly upon the rear movable sections, the effect being communicated through the series at 5 each side of the jack by their successive contact with one another. When the machine is started and the cross-head and jack rise, the upper is trued laterally by the gaging surfaces 102, and is clamped against the molding recess 14 in the 10 die-block. The pull of the connections 90 is relaxed, and the rear movable nailing sections freed so the springs 84 are allowed to force all the sections to a relation with the heel-seat determined by the engagement of the rolls 64 with 15 the counter-portion of the upper, and the contact of the successive sections with one another. Following this, the wedges 104 positively lock the movable nailing sections by their insertion between the forward sections and a fixed wall, and 20 the nails N, which have previously been delivered to the passages 42 in the sections and to the fixed passages 24 by the loader 48, are driven into the heel-seat by engagement of the descending head 30 with the plungers 54 of the drivers 50 25 in the sections and by the drivers 28 fixed in said head. Upon the elevation of the head 30 and the lowering of the cross-head 18, the various elements are restored to their normal positions.
- Having described my invention, what I claim 30 as new and desire to secure by Letters Patent of the United States, is:
1. In a machine for inserting fastenings, a work-support, and a plurality of fastening-inserting mechanisms each arranged to move toward and from the support about an individual axis, the axes about which the mechanisms move being substantially parallel.
  2. In a machine for inserting fastenings, a work-support, and a plurality of fastening-inserting mechanisms each arranged to move toward and from the support about an individual axis, the axes of the mechanisms being fixed against movement and substantially parallel.
  3. In a machine for inserting fastenings, a movable work-support, and a plurality of fastening-inserting mechanisms arranged to oscillate toward and from the support, each mechanism being movable about an axis individual to it and all the axes about which such movements occur extending in the direction of movement of the support.
  4. In a machine for inserting fastenings, a movable work-support, means for moving the support under the power of the machine, and a plurality of fastening-inserting mechanisms arranged to oscillate toward and from the support, each mechanism being movable about an axis individual to it and extending in the direction of power-movement of the support.
  5. In a shoe-nailing machine, a shoe-support, a generally horizontal abutment with which the support co-operates, and a plurality of fastening-inserting mechanisms co-operating with the support and abutment and each arranged to oscillate about a substantially vertical axis individual to the respective mechanism.
  6. In a machine for nailing the heel-portions of shoes, a shoe-support, a plurality of nailing sections having body-portions extending outwardly side by side from the axis of the support, an arm fixed against movement upon each body-portion and extending at an angle thereto, and a pivotal mounting for each arm.
  7. In a machine for nailing the heel-portions of shoes, a shoe-support, a plurality of nailing
- sections having body-portions extending outwardly side by side from their points of cooperation with the support, an arm carrying each body-portion and extending at an angle thereto, and a pivotal mounting for each arm, said mountings being arranged in groups at opposite sides of the support.
8. In a shoe-nailing machine, a jack, a die-block with which the jack co-operates, said die-block having openings through which nails may be driven and being arranged for contact with the jacked work at both the inner and outer sides of the openings, and a plurality of nailing sections co-operating with the jack and die-block and each arranged to oscillate about an individual axis.
9. In a fastening-inserting machine, a plurality of movable fastening-inserting mechanisms one of which is arranged for contact with the work to position the mechanism with respect thereto, there being contact means associated with the thus-located mechanism and an adjacent mechanism and arranged to solely determine the position of the latter toward and from the work.
10. In a nailing machine, a series of movable nailing mechanisms one only of which is arranged for contact with the work to position a mechanism with respect thereto, there being contact means associated with the thus-located mechanism and the succeeding mechanisms of the series, such contact means being arranged to position said succeeding mechanisms.
11. In a fastening-inserting machine, a movable fastening-inserting mechanism provided with a member arranged for contact with the work, an associated fastening-inserting mechanism, and contact means carried by the mechanisms and arranged to locate the second mechanism with respect to the work and under the control of the first.
12. In a fastening-inserting machine, a movable fastening-inserting mechanism provided with a member arranged for contact with the work, means for fixing the contact member in different positions upon its mechanism, an associated fastening-inserting mechanism, and contact means carried by the mechanisms and arranged to locate the second mechanism with respect to the work and under the control of the first.
13. In a shoe-nailing machine, a shoe-support, a series of movable nailing sections one of which is arranged for locating contact with a supported shoe, and cam members carried by the sections and acting upon succeeding sections of the series to locate them.
14. In a shoe-nailing machine, a shoe-support, a series of movable nailing sections one of which is arranged for locating contact with a supported shoe, and members carried by the sections and having cam-surfaces inclined outwardly and rearwardly from the breast-line of the supported shoe and having contact with an adjacent section.
15. In a shoe-nailing machine, a shoe-support, a series of movable nailing sections one of which is arranged for locating contact with the supported shoe, cam members carried by the sections and acting upon the succeeding sections of the series to locate them, and means arranged to vary the normal relation between a cam member and the surface upon which it acts.
16. In a machine for inserting fastenings, a work-support, a plurality of fastening-inserting

- mechanisms each arranged to move in a definite path toward and from the support about an individual axis, a locating member carried by one inserting mechanism for contact with the work, and contact means carried by the other mechanisms and arranged to locate them under the control of that first mentioned. 80
17. In a shoe-nailing machine, a shoe-support, a generally horizontal abutment with which the support co-operates, a plurality of fastening-inserting mechanisms cooperating with the support and abutment and each arranged to oscillate about a substantially vertical axis individual to the respective mechanism, a locating member carried by one nailing mechanism for contact with the work, and cam means connecting the other mechanisms to determine their positions. 85
18. In a machine for nailing the heel-portions of shoes, a shoe-support, nailing mechanism arranged to contact with a supported shoe toward the rear of the heel-portion and to be located thereby, and another nailing mechanism situated toward the breast-line of the shoe and contacting with the first-mentioned mechanism to be located by it at different distances from the support. 90
19. In a fastening-inserting machine, a work-support, a plurality of fastening-inserting mechanisms arranged to oscillate toward and from the support, and means arranged to vary independently the axes of oscillation of the mechanisms. 95
20. In a fastening-inserting machine, a work-support, a plurality of fastening-inserting mechanisms arranged to oscillate toward and from the support, an eccentric-mounting for an inserting mechanism, and means arranged to fix said eccentric-mounting in different rotary positions. 100
21. In a machine for nailing the heel-portions of shoes, a shoe-support, a plurality of nailing sections having body-portions extending outwardly side by side from the axis of the support, an arm extending at an angle from each body-portion, and an adjustable eccentric upon which each arm is mounted. 105
22. In a fastening-inserting machine, a plurality of movable fastening-inserting mechanisms one of which is arranged for contact with the work to position the mechanism with respect thereto, there being contact means associated with the thus-located mechanism and an adjacent mechanism and arranged to position the latter, and an adjustable mounting for each mechanism. 110
23. In a shoe-nailing machine, a shoe-support, a series of oscillatory nailing sections one of which is arranged for locating contact with a supported shoe, cam members carried by the sections and acting upon the succeeding sections of the series to locate them, and adjustable eccentricities about which the sections oscillate. 115
24. In a fastening-inserting machine, a work-support, a series of movable fastening-inserting mechanisms one of which is arranged for contact with the supported work and is located thereby, others of the series being provided with contact means normally fixed against movement thereon and arranged to locate them in their fastening-inserting positions, and means acting upon one of the last-mentioned mechanisms of the series for moving all of said mechanisms. 120
25. In a fastening-inserting machine, a work-support, a series of movable fastening-inserting mechanisms, a mechanism at one extremity of the series being arranged for contact with the supported work to be located thereby, said mechanism and the remainder of the series being provided with contact means normally fixed against movement thereon and arranged to locate said remaining mechanisms in their fastening-inserting positions, and means acting upon the mechanism at the opposite end of the series from that in engagement with the work for moving all of said mechanisms toward the work. 125
26. In a machine for nailing the heel-portions of shoes, a shoe-support, a series of movable nailing sections supported at one side of the heel-portion of a supported shoe and arranged for contact with one another, a locating member carried by the rear section and arranged for contact with the shoe, and a spring acting upon the forward section and arranged to force the successive sections together to positions controlled by the rear section. 130
27. In a machine for nailing the heel-portions of shoes, a shoe-support, a series of movable nailing sections supported at one side of the heel-portion of a supported shoe and arranged for successive contacts with one another, a locating member carried by the rear section and arranged for contact with the shoe, a spring acting upon the forward section and arranged to force the successive sections together to positions controlled by the rear section, and cams carried by the sections and determining the position of the sections other than that contacting with the work. 135
28. In a fastening-inserting machine, a work-support, a plurality of fastening-inserting mechanisms movable toward and from the support, means for moving the plural mechanisms toward the support, means acting upon one only of the plural mechanisms for moving it from the support, and means supported wholly upon the mechanism thus moved and contacting with an adjacent mechanism for communicating the movement thereto. 140
29. In a fastening-inserting machine, a work-support, a series of fastening-inserting mechanisms movable toward and from the support, means for moving the series of mechanisms toward the support, means acting upon one of the series for moving it from the support, and contact members each individual to one of the series and arranged to transmit such movement to another mechanism of the series. 145
30. In a fastening-inserting machine, a work-support, a series of fastening-inserting mechanisms movable toward and from the support, means acting upon one of the series for moving it from the support, means acting upon one of the series for moving it toward the support, and cams arranged to transmit both of such movements to other mechanisms of the series. 150
31. In a fastening-inserting machine, a work-support, a series of fastening-inserting mechanisms movable toward and from the support, means acting upon a terminal mechanism of the series for moving it toward the support, means acting upon the mechanism at the opposite extremity of the series for moving it from the support, and connections arranged to transmit the movements to the intermediate mechanisms. 155
32. In a machine for nailing the heel-portions of shoes, a shoe-support, a series of nailing sections co-operating with the support, means for moving the series of sections toward the support, connections between the support and a section at one extremity of the series for moving said section from the support, and connections be- 160

- between the sections for transmitting such movement from the support through the series.
33. In a machine for nailing the heel-portions of shoes, a shoe-support, a series of nailing sections co-operating with the support, a spring acting upon a section at one extremity of the series for moving the section toward the support, connections between the support and a section at the opposite extremity of the series for moving said section from the support, and connections between the sections for transmitting through the series the movements both toward and from the support.
34. In a fastening-inserting machine, a movable work-support, a series of fastening-inserting mechanisms movable toward and from the support, and a tension member connecting the support to an inserting mechanism and arranged to move said mechanism relatively to the support.
35. In a machine for nailing the heel-portions of shoes, a movable shoe-support, a series of nailing sections movable toward and from the support, a member movable with the support and connected to one only of the nailing sections, said member transmitting the movement of the support to said section, and means for transmitting the movement of such section to the associated sections.
36. In a machine for nailing heel-portions of shoes, a movable shoe-support, a series of nailing sections movable toward and from the support, a member movable with the support and connected to one only of the nailing sections, said member transmitting the movement of the support to said section, and cams arranged to transmit the movement of said section to the associated sections.
37. In a shoe-nailing machine, a vertically movable cross-head, a jack movable upon the cross-head, horizontally movable nailing sections co-operating with the jack, and connections to the cross-head for moving the sections independently of the jack.
38. In a shoe-nailing machine, a vertically movable cross-head, a jack movable upon the cross-head, series of nailing sections horizontally movable at opposite sides of the jack, and a flexible member connecting the cross-head to each series of nailing sections.
39. In a shoe-nailing machine, a vertically movable shoe-support, horizontally movable nailing sections cooperating with the support, a spindle carried by a nailing section, and a roll rotatable upon and free to move longitudinally of the spindle and arranged for contact with a supported shoe.
40. In a fastening-inserting machine, a movable fastening-inserting mechanism, a movable actuating member for the inserting mechanism, yieldable means for forcing the inserting mechanism to operating position, and a locking member acting in the movement of the actuating member for retaining the inserting mechanism against yield, said member and inserting mechanism having contacting surfaces intersecting the direction of movement of the mechanism.
41. In a fastening-inserting machine, a movable fastening-inserting mechanism, a movable actuating member for the inserting mechanism, yieldable means for forcing the inserting mechanism to operating position, a member fixed against movement relatively to the inserting mechanism, and a locking member movable between the fixed member and inserting mechanism.
42. In a fastening-inserting machine, a movable fastening-inserting mechanism, a movable actuating member for the inserting mechanism, yieldable means for forcing the inserting mechanism to operating position, a member fixed against movement relatively to the inserting mechanism, and a locking member yieldably mounted upon the actuating member and movable between the fixed member and inserting mechanism.
43. In a fastening-inserting machine, a die-block, a fastening-inserting mechanism movable in co-operation with the die-block, and a locking wedge movable between the inserting mechanism and die-block.
44. In a fastening-inserting machine, a die-block, a fastening-inserting mechanism movable in co-operation with the die-block, a locking wedge movable between the inserting mechanism and die-block, and a yieldable mounting for the wedge.
45. In a shoe-nailing machine, a shoe-support, a series of nail-inserting mechanisms movable toward and from the support, means acting upon a terminal mechanism of the series for moving all the mechanisms toward the support, and a member movable into contact with such terminal mechanism for locking the series against movement from the support.
46. In a shoe-nailing machine, a shoe-support, a die-block, a series of nailing mechanisms co-operating with the die-block and movable toward and from the support, a spring acting upon a terminal mechanism of the series to force said series toward the support, and a locking wedge movable between said terminal mechanism and the die-block.
47. In a shoe-nailing machine, nailing mechanism, a shoe-support movable toward and from the nailing mechanism, and a gage member having portions arranged to contact with opposite sides of the sole of a shoe on the support, the opposite contact-surfaces of the gage diverging outwardly in the direction of the support.
48. In a shoe-nailing machine, nailing mechanism, a shoe-support movable toward and from the nailing mechanism, a gage member having portions arranged to contact with opposite sides of a shoe on the support, the opposite contact-surfaces of the gage diverging outwardly in the direction of the support, and a mounting for the gage member permitting it to yield in the direction of movement of the support.
49. In a machine for nailing the heel-portions of shoes, a die-block, a work-support movable vertically into co-operation with the die-block, and a gage member mounted at the front of the die-block and having portions arranged for engagement with opposite sides of the shoe at the bottom and adjacent to the breast-line only.
50. In a machine for nailing the heel-portions of shoes, a die-block, a work-support movable vertically into co-operation with the die-block, and a gage member having a shank yieldable vertically upon the die-block and downwardly diverging surfaces for contact with opposite sides of a supported shoe.
51. In a machine for nailing the heel-portions of shoes, a pressure-abutment provided with a surface for contact with the portion to be nailed, nail mechanisms co-operating with the abutment, a jack-post, the abutment and jack-post being relatively movable, a jack-top, and a universal joint connecting the top and post, said joint having contacting surfaces curved about a

point lying substantially in the pressure-surface of the abutment during the nailing operation.

52. In a heel-seat-nailing machine, a die-block provided with a surface for contact with the heel-seat of a shoe to be nailed, nailing mechanisms co-operating with the die-block, a jack-post moveable toward and from the abutment, a jack-top,

and a ball-and-socket joint connecting the top and post, the contacting surfaces of the ball and socket being curved about a center which lies substantially in the contact-surface of the die-block during the nailing operation.
